UNITED STATES PATENT OFFICE.

HUGO THUEMLER, OF PITTSBURG, PENNSYLVANIA.

DESIGN FOR A DRINKING-TUMBLER.

No. 38,003.

Specification for Design.

Patented May 8, 1906.

Application filed March 23, 1906. Serial No. 307,727. Term of patent 3½ years.

To all whom it may concern:

Be it known that I, HUGO THUEMLER, a subject of the German Emperor, residing at Pittsburg, in the county of Allegheny and State of Pennsylvania, have invented a new, original, and ornamental Design for a Drinking-Tumbler, of which the following is a specification, reference being had to the accompanying drawing, forming part thereof.

The figure is a perspective view of a drinking-tumbler, showing my new design.

I claim—

The ornamental design for a drinking-tumbler as shown.

HUGO THUEMLER.
